JEWELRY BOX

Richard C. J. Palson, Medfield, Mass., assignor to American Gold Chain Company, Inc., New York, N.Y., a corporation of New York

Filed Sept. 12, 1966, Ser. No. 3,823

Term of patent 14 years

(Cl. D58—12.7)

FIG. 1 is a perspective view of a jewelry box showing my new design;

FIG. 2 is an end view thereof;

FIG. 3 is a bottom plan view thereof;

FIG. 4 is a rear elevational view thereof; and

FIG. 5 is a perspective view showing the jewelry box in opened position.

I claim:

The ornamental design for a jewelry box, substantially as shown.
